UNITED STATES PATENT OFFICE.

JOHN SHUTTLEWORTH, OF ALTRINCHAM, ENGLAND, ASSIGNOR TO LINOTYPE AND MACHINERY LIMITED, OF LONDON, ENGLAND, A LIMITED LIABILITY COMPANY OF GREAT BRITAIN.

PRINTING-PRESS CYLINDER FOR ENABLING THE PRINTING, IMPRESSION, OR OFFSET SURFACES TO BE ADJUSTED.

Application filed June 23, 1924, Serial No. 721,611, and in Great Britain July 5, 1923.

This invention relates to improvements in printing press cylinders for enabling the printing, impression or offset surfaces to be adjusted.

5 When plating the form cylinders of printing presses, it is frequently necessary to adjust a plate in a direction longitudinal of said cylinders, so that in the case of a cylinder having two plates in side by side relationship, the marginal space between the opposed plate edges may be increased or decreased for the purpose of producing a wider or narrower margin between the resultant printed matter or, in the case of a 10 plurality of co-operating cylinders, the printed matter on the plates of the respective cylinders may be brought into correct register.

It is also desirable for corresponding 20 longitudinal adjustments of the co-operating blankets of offset presses to be made relatively to the axes of the impression or offset cylinder shafts, and although in the constructional form of the invention hereinafter described, a form cylinder is referred to throughout, it is to be understood 25 that the invention is equally applicable to impression or transfer cylinders or sections thereof.

30 The object of the present invention is to provide means whereby the above-named adjustments can be more readily effected than has heretofore been practicable, said means including an arrangement for enabling the respective cylinder or sections 35 thereof to be adjusted longitudinally on the respective cylinder shaft.

The invention will now be described by reference to the accompanying drawings in 40 which:—

Figure 1 is an end elevation of one constructional form of said invention;

Figure 2 is a longitudinal section taken generally on the line 2—2 of Figure 1;

45 Figure 3 is an end elevation of a second constructional form of the invention;

Figure 4 is a longitudinal section taken generally on the line 4—4 of Figure 3, and

50 Figure 5 is a left-hand elevation of certain parts shown in Figure 4, drawn to a larger scale.

Like reference numerals indicate like

parts in the different arrangements illustrated.

In Figures 1 and 2, wherein the invention 55 is shown as applied to a form cylinder adapted to have plates secured thereon in side-by-side relationship, the said cylinder is constructed of two main co-axial parts or sections 1, 2, both secured to the same shaft 3, as by dovetail or other splines or feathers 4, which admit of those sections moving on the shaft only in endwise direction. Each of the sections 1, 2, is provided with means for securing thereto one or more printing forms; in the example illustrated in Figure 1, accommodation is provided on the section 1 for two printing forms which are respectively designated by the numerals 5, 6. The means for attaching these forms to the section 1 and for stretching them thereon are not shown in the drawings, as they constitute no part of the present invention.

At the outer side of each of the cylinder sections 1, 2, the shaft 3 has rigidly secured 75 to it an arm or bracket 7, in which is journaled a set screw 8 whose inner end is threaded into the adjacent end of the respective cylinder section, say the section 1, so that by turning this set screw, the said section will be traversed in one or other direction along the shaft 3 to move the forms 5, 6 on that section nearer to or farther from the forms on the cylinder section 2. By these means either of the sections 1, 2 with 80 the forms thereon can be moved nearer to or farther from the other one, as when one of the two set screws 8 is adjusted, or both of the said sections can be moved outwards or inwards by turning both of these screws. 85

The set screws 8 are each prevented from moving axially in the respective bracket 7 in one direction by the head of said screw, and in the other direction by a collar 9 fast on the screw, while means such as lock nuts 10, are provided for preventing unintentional rotation of the screws and axial movement of the cylinder sections 1, 2.

To permit of two printing forms carried 100 by the same cylinder section being co-axially adjusted independently of each other, each such section, as shown in Figures 3 and 4, is formed of two independent segments 11, 12 or 13, 14. These segments are adjustable

axially, but not otherwise, on the form cylinder shaft 3, this restriction being conveniently imposed, as in the before described example, by slidably connecting said 5 segments to the shaft by splines or feathers 4, and, if desired, the adjustment of each of the segments may be effected by set screws similar to those hereinbefore described in connection with Figure 2.

10 By reference to Figure 3, it will be seen that the two segments 11, 12, as do also the segments 13, 14, abut against each other along the line 15, and that the contacting surfaces here involved, are free to slide relatively to each other in a direction parallel with the axis of the shaft 3. By reference to Figure 4, it will further be seen that the general contour of each of the two segments 11, 12 or 13, 14 differs from that of the other 15 inasmuch as the parts thereof which contact with the shaft 3, are in staggered relationship and intercalate each with the other, with a sufficient allowance of room between them to admit of the aforesaid sliding movement.

20 In the example now under review, the different segments are so connected together that the two 11 and 13 or 12 and 14 can be simultaneously adjusted from either end of the cylinder or adjusted independently of 25 each other as occasion may require. For this purpose a screw shaft 16 extends longitudinally through said two sections which, to avoid unnecessary circumlocution, are here assumed to be the segments 11, 13, although the description equally well applies to the segments 12, 14. This screw shaft 16, is rotatably supported at each end in a bracket 7 fast to the shaft 3, axial movement thereof being prevented by collars 17 30 fast to one end of the screw shaft on either side of the respective bracket 7; at the outer side of the bracket 7 at the opposite end of the screw shaft 16, there is secured a similar collar 17 and at its extreme ends the said 35 shaft is of square or other non-circular form so as to enable it to be engaged by a correspondingly shaped key or spanner by which it can be rotated.

At the right-hand end of the screw shaft 50 16 (as viewed in Figure 4) there is provided the screwed portion 18 which is threaded into the adjacent end of the segment 13, and at the opposite end of the said shaft passes axially through a bush 19 which is externally screw-threaded to engage with the corresponding end of the segment 11, the threads on the parts 18 and 19 being one right-handed and the other left-handed. The outer end of the bush 19 is formed with a 55 flange 20 integral therewith, having peripheral holes or recesses 21 for receiving a "tomy" or like implement to enable it to be turned about its axis, and adjacent to this flange there is rigidly secured to the screw 60 shaft 16, a collar 22 against which the flange 65

can be forced in close frictional engagement or held in operative engagement by screws 24 hereinafter described, so as, in effect, to lock the said screw shaft to the bush 19. Lock nuts 23 are provided on the threaded 70 portion 18 of the screw shaft 16 and on the bush 19 by tightening which against the outer ends of the segments 13, 11 the latter can be secured in any desired position of 75 adjustment.

By referring to Figure 5, it will be seen that means are provided for limiting the angular motion between the bush 19 and the screw shaft 16, said means consisting of the beforementioned screws 24 removably attached to the flange 20 and engaging with arcual slots 25 in the collar 22, the length of these slots being sufficient to provide for any such slight adjustment of segment 11, as might be called for by a form having 80 inaccurately positioned thereon.

When, with the before-described arrangement, it is desired to simultaneously adjust both of the cylinder segments 11, 13 inwards or outwards, the lock nuts 23 are released, and the screw shaft 16 is turned in the direction necessary to effect said adjustment, the bush 19 at this juncture, rotating as if integral with the screw shaft 16 and therefore moving the segment 11 in one direction, while the screwed portion 18 of said shaft 16 moves the segment 13 in the reverse direction. This adjustment serves for effecting a material increase or decrease of marginal space between the forms on the segments 11, 13. When, however, a form is inaccurately positioned on the segment 11, this can be remedied by loosening the lock nut 23 engaging the end of the latter, slackening the screws 24, and turning the bush 19 relatively to the screw shaft 16 and thereafter tightening the said lock nut and screws. In the case of a form being inaccurately positioned on the segment 13, the necessary adjustment is effected by loosening the lock 90 nut 23 engaging the end of the latter, loosening screws 24, and turning the shaft 16 in the required direction, subsequently tightening the respective lock nut 23 and the screws 24. If the arcual lengths of the slots 95 25 be insufficient to admit of the full adjustment of the inaccurately positioned form, the screws 24 can be temporarily removed from the flange 20 and the bush 19 turned to the necessary extent independently of the collar 22, the subsequent locking of the screw shaft 16 being effected by tightening the lock nuts 23.

It is to be understood that although the adjusting means shown in Figures 3, 4 and 100 5 have been herein described only in connection with cylinders having circumferentially aligned segments, said means can be equally well applied to cylinders of the construction represented in Figures 1 and 2, without 105 110 115 120 125 130

departing from the spirit of the invention.

Having described my invention, I declare that what I claim and desire to secure by Letters Patent is:—

- 5 1. The combination with a printing press cylinder and the shaft of said cylinder, of a plurality of co-axial cylinder sections and means operative from either end of the cylinder operative to adjust said sections axially on the shaft alternatively either simultaneously or independently of each other.
- 10 2. In a printing press cylinder, the combination of a plurality of co-axial cylinder sections each comprising a plurality of separate circumferentially aligned segments and means operative to adjust said segments independently in a direction parallel with the axis of the cylinder either simultaneously or independently of each other.
- 15 3. In a printing press cylinder, the combination of a plurality of co-axial cylinder

sections each comprising a plurality of separate circumferentially aligned segments engaging the cylinder shaft by parts intercalating with each other and means operative 25 to adjust said segments independently in a direction parallel with the axis of the cylinder.

4. In a printing press cylinder, the combination of a plurality of co-axial cylinder 30 sections each comprising a plurality of separate circumferentially aligned segments engaging the cylinder shaft by parts intercalating with each other and means operative 35 to adjust said segments in a direction parallel with the axis of the cylinder either simultaneously or independently of each other.

In testimony whereof I have affixed my signature hereto.

JOHN SHUTTLEWORTH.
